UNITED STATES PATENT OFFICE.

JOHN E. LESNEUR, OF NASHVILLE, TENNESSEE.

BRICK-MACHINE.

SPECIFICATION forming part of Letters Patent No. 355,876, dated January 11, 1887.

Application filed April 13, 1886. Serial No. 198,680. (No model.)

To all whom it may concern:

Be it known that I, JOHN E. LESNEUR, a citizen of the United States, residing at Nashville, in the county of Davidson and State of Tennessee, have invented certain new and useful Improvements in Brick-Machines; and I do hereby declare the following to be a full, clear, and exact description of the invention, such as will enable others skilled in the art to which it appertains to make and use the same.

My invention relates to that class of brick-machines in which a series of molds or mold-boxes are linked together to form an endless series, and are pressed beneath the charger or pug-mill, from whence they pass to the presser; and it has for its object to provide a simple, durable, and effective machine of but few parts, and therefore not liable to get out of repair; and it consists of the parts and combinations of parts hereinafter described and claimed.

In the accompanying drawings, forming a part of this specification, Figure 1 is a side elevation, the pug-mill being in section, of my improved machine; Fig. 2, a plan view of the chain of mold-boxes and the chain of cover-plates; Fig. 3, an end elevation; Fig. 4, an end and side view of plunger and roller; Fig. 5, a vertical cross-section on line xx , Fig. 1; Fig. 6, a side elevation of about one-half of the machine, showing a modification; and Fig. 7 an enlarged detail view of the right-hand end of Fig. 1.

Similar letters refer to similar parts throughout the several views.

A represents the frame-work of my machine, of any suitable size and material. On this frame suitable journal-boxes, B, are provided at each end for the shafts C of the polygonal sprocket-wheels D, D', around which passes the endless chain of mold-boxes, and on a longitudinal beam, n, supported at about the middle of the frame-work on two uprights, 45 n', journal-boxes B' are provided for the shafts C' of the sprocket-wheels N, around which passes the endless chain of cover-plates M.

E E are tracks or ways, the former being located at about midway the height of the machine, and their middle portions supported on spiral or other springs, p, secured to the upper ends of short uprights F, and their ex-

tremities by uprights F'; which extend from the upper sills of the frame, while the track E is secured to the frame in any suitable manner sufficiently high above its bottom sills to permit of the unobstructed passage of the endless chain of mold-boxes when they are returning empty to be charged by the pug-mill.

H is an inclined pressure-plate, which extends from immediately in the rear of the front sprocket-wheel, D, to near the rear sprocket-wheel, D'. This plate is suitably supported at its ends by the cross-beams of the machine, while its middle portion is supported by the eye-bars P, three (more or less) on each side of the machine, as shown in dotted lines, Fig. 1 and full lines in Fig. 5. These bars depend downwardly from the upper pressure-plate, G, and are connected together at their upper and lower ends by cross-bars r, which form the support for both pressure-plates G and H and receive the strain put on the clay in the mold-boxes.

The plate H is on a level from the point 1, Fig. 1, to point 2, and is inclined at an angle of about fifteen or twenty degrees from 2 to 3, and slightly inclines from 3 to 4, and from this point is again level to 5, where it first receives the rollers m, Fig. 4, of the plungers K after the same have passed the sprocket D, inclined strips s being secured to the frame at this point, as clearly shown on right-hand side of Figs. 1 and 7, one on each side, to deflect the rollers m onto the plate H.

The endless chain of mold-boxes is composed of the links a, hinged together by link-pins b, the wheels c, plungers K, rollers m, and mold boxes or frames d. The pins b project outwardly on each side of the chain a short distance for the purpose of providing axles for the wheels c. The boxes d, as clearly shown in the side elevations, slope or are inclined from their tops to their bottoms at each side, forming when in line, a V-shaped opening or space, e, between every two boxes, one object of which is to present to the pug-mill and cover-plates one continuous unbroken series of mold-boxes, the upper edges of which being in contact form a moving table or flat surface having no openings or joints, into which clay may find its way, and thus obstruct or interfere with the operation of the chain. Another object in thus constituting the mold-

boxes is to afford a ready escape for any stray particles or lumps of clay which might find their way between the buckets when they are spread apart in passing over the sprocket-wheels. The sharp upper edges of the boxes when brought together will cut the clay, and the gradually-widening space between them will readily permit of, and, in fact assist, its escape, owing to the fact that the boxes, as they fall in line after passing over the sprocket-wheels, gradually contract the space between them, and thus force the clay down or toward their bottoms. The mold-boxes, as here represented, have a partition in their center, so that two bricks may be formed in each box; but, if desired, they may be enlarged, so as to accommodate four or more. The plungers K are accurately fitted to the mold-boxes and form the bottoms thereof. The rollers m are journaled in lugs formed integral with and projecting from the bottoms of the plungers, their shafts d' projecting outwardly on each side a short distance beyond the side of the lugs, so as to meet the inclined strips s, above referred to, when the wheel D has been passed to deflect the rollers m onto plate H. The wheels d run or travel on the tracks or ways E E', the former of which keep the charged boxes on a level and well up to the pressure-plate G and prevent all sagging, at the same time this track being supported on springs at its middle portion where the strain is greatest, will yield to any undue strain which might, perhaps, if not relieved, break the track, while over the latter, E', the boxes are returned to be charged.

M is an endless chain of cover-plates passing around the sprocket-wheels N. These plates are smooth flat pieces of metal or other suitable material hinged together by link-pins m' and links m'', and are each adapted to accurately cover one mold-box, and the plates are so adjusted relative to the mold-boxes that when they are in operative position they will each meet and exactly cover one mold-box and travel with the same from the point where the pressure is first applied to the clay through the plunger and lower pressure-plate to the point where the chain of plates begins to recede from the chain of mold-boxes, and thus uncover the same and permit the bricks to be ejected from the molds by the plunger, the rollers of which begin the ascent of inclined plane between 3 and 2 at this point in the travel of the chain of boxes. The plates forming part of the chain are secured to or formed integral with the links thereof, the latter being hinged together by the pins m', which catch in recesses formed in the corners of the wheels B', so as to insure the chain against slipping. This is true also of the pins b and sprocket-wheels B. The plates are cut away on their sides precisely the same as the mold-boxes and for the same purpose. The chain M passes between the chain of boxes and the pressure-plate G, the pressure from the latter being exerted on the backs of the plates, which

are provided with friction-rollers o, so that the passage of the chain will be rendered easy.

O is a pug-mill provided with the ordinary vertical shaft driven by bevel gear-wheels, and blades and knives for mixing and tempering the clay and forcing the same into the mold-boxes as they pass under the opening in the bottom of the mill.

O' is a skimming-knife, which levels the clay in the molds even with the tops or upper surface of the boxes.

In Fig. 6 I show a modification of the machine, in which all the parts are the same, excepting the lower pressure-plate, which has an opening or slot cut through it about two-thirds of its length from the front or feeding end of the machine, through which a large wheel, R, projects directly in the track of the rollers m. This wheel is journaled in boxes supported by an additional pair of eye-bars, P', somewhat longer than the bars P, which are hung in the same manner as the said bars P. The rollers c, in their travel over plate H, must also travel over the wheels R, and thus put an immense but momentary pressure on the clay.

I may discard the wheels c and permit the pins b to slide over the tracks E E', if I so desire; but I prefer to use the wheels, as they render the operation of the machine easy. I do not intend using the wheel R at all times, and do not desire to be restricted to the use thereof, as I may use merely the lower pressure-plate in connection with the rollers and get good results.

S is a chain which passes around a sprocket-wheel, T, on the shaft C, and leads over sprocket-wheel S' on the shaft C' of the wheel N, being crossed so as to rotate the sprocket-wheels D' and N in opposite directions, and thus cause the endless chain of plates M and chain of mold-boxes to travel together in the same direction at their point of contact. The wheels D, D', and N are made of the same diameter to give the same rate of speed to the chains.

In operation the clay is placed in the pug-mill O, and its shaft being given motion mixes and tempers the clay, forcing the same downward in a spiral direction and out through its bottom opening into the mold-boxes, the same having been set in motion by the shaft C through the medium of any suitable power applied to the gear-wheel thereon, the knife O' skims the clay in the boxes off even with the upper surfaces of the same, and they are conveyed along until they meet the cover-plates, where the first pressure is applied to the clay, the rollers m, beginning the ascent of the plane between 4 and 3, gradually forcing the plunger up into the boxes and compressing the clay against the cover-plates, the latter being braced by the pressure-plate G until the plates recede from the mold-boxes, when the rollers ascend the plane 3 2, gradually forcing the bricks out of the boxes until the level plane 2 1 is reached, where the upper surfaces of the

plungers become flush with the upper surfaces of the boxes and the bricks removed from the same by the attendant, the plungers still remaining flush with the boxes until the shafts 5 d' of the rollers m come in contact with the inclined strips s , by which they are deflected onto the level plane beginning at 4, and are again in position for operation. If the wheel R is used, the operation is the same, excepting 10 that a tremendous but momentary pressure is exerted on the clay by the rollers passing over the same.

Having thus described my invention, what I claim as new, and desire to secure by Letters 15 Patent, is—

1. In a brick-machine, the combination of the frame A , the tracks or ways $E E'$, inclined pressure-plate H , endless chain of mold-boxes, plungers K , sprocket-wheels $D D'$, the chain 20 of cover-plate M , sprocket-wheels N , pressure-plate G , and suitable eye-bars for supporting the same, substantially as and for the purpose set forth.

2. In a brick-machine, the combination of 25 the endless chain of mold-boxes, the pins b , wheels c , the plungers K , having the lugs, rollers m , tracks or ways $E E'$, lower pressure-plate, H , upper pressure-plate, G , and the endless chain of cover-plates M , substantially as 30 described.

3. In a brick-machine, the combination of the frame A , sprocket-wheels $D D'$, the chain of mold-boxes provided with the wheels c , the plungers K , inclined pressure-plate H , and 35 the tracks or ways $E E'$, the track or way E having a yielding support, substantially as and for the purpose described.

4. A track or way for the rollers or wheels of an endless chain of mold-boxes, having a 40 yielding support, substantially as described.

5. The combination, in a brick-machine, of the endless chain of mold-boxes, the plungers K , the rollers m , the shafts d' , the inclined strips s , and the pressure-plate H , substantially 45 as and for the purpose described.

6. The combination, in a brick-machine, of the endless chain of mold-boxes, the wheels c , the plungers K , the rollers m , the tracks or ways $E E'$, the slotted pressure-plate H , the wheel R , and eye-bar P , substantially as and 50 for the purpose described.

7. An endless chain of mold-boxes for a brick-machine, consisting of the links a , link-pins b , wheels c , and boxes d , the latter being sloped from their tops to their bottoms, so as 55 to form an unbroken table or surface when in a horizontal position, substantially as described.

8. The combination of the horizontally-moving endless chain of mold-boxes, the plungers 60 K , provided with lugs, the rollers m , and the longitudinal pressure-plate H , so constructed as to present inclines of different angles and planes of different levels, substantially as described.

9. The combination, in a brick-machine, of the endless chain of mold-boxes, the upper pressure-plate, G , the eye-bars P , and the lower pressure-plates, H , substantially as described. 65

10. The brick-machine hereinbefore described, comprising a suitable frame, sprocket-wheels $D D' N$, shafts $C C'$, tracks or ways $E E'$, the former yieldingly supported, the inclined pressure-plate H , the endless chain of 70 mold-boxes provided with the links a , pins b , wheels c , plungers K , and rollers m , the endless chain of cover-plates M , linked together and provided with friction-rollers, the pressure-plate G , eye-bars P , a suitable charger or 75 pug-mill, O , skimming-blade O' , crossed belt S , and wheels S' and T , substantially as described.

In testimony whereof I affix my signature in presence of two witnesses.

JOHN E. LESNEUR.

Witnesses:

JOHN M. GANT,
LEMUEL R. CAMPBELL.

It is hereby certified that the name of the patentee in Letters Patent No. 355,876, granted January 11, 1887, for an improvement in "Brick-Machines," was erroneously written and printed "John E. Lesneur," whereas said name should have been written and printed *John E. Lesueur*; and that said Letters Patent should be read with this correction therein that the same may conform to the record of the case in the Patent Office.

Signed, countersigned, and sealed this 1st day of March, A. D. 1887.

[SEAL.]

Countersigned:

R. B. VANCE,
Acting Commissioner of Patents.

D. L. HAWKINS,
Acting Secretary of the Interior.
